TOP ROLL

**Leland D. Cobb, Forestville, Conn., assignor to
General Motors Corporation, Detroit, Mich., a
corporation of Delaware**

Application December 31, 1941, Serial No. 425,145

8 Claims. (Cl. 19—142)

This invention relates to top rolls for textile machinery and particularly to top rolls for roving frames, spinning frames and similar devices wherein a roving, sliver, thread or the like is subjected to an attenuating operation by passing it under tension between top and bottom rolls that are urged into peripheral rolling contact.

It is common practice to provide top rolls with reduced end portions which rotatably and frictionally engage within slots in a guiding frame while weighted arms frictionally engage these reduced end portions to urge the top rolls downwardly into supported rolling engagement with bottom rolls. A spinning or like machine has many top rolls, and the friction of these rolls against their guide frames and against the weighted arms causes objectionable power loss as well as considerable wear which necessitates frequent replacement of worn parts.

An object of this invention is to provide an improved top roll of simple construction and which overcomes the above-noted objectionable features. A further object is to provide an improved top roll which embodies few parts and is so constructed that it does not rotatably engage the guide slots and weighted arms. Another object is to provide a unit-handling top roll having a through shaft antifrictionally and demountably secured in a pair of interconnected top roll members.

To these ends and also to improve generally upon devices of the character indicated, the invention consists in the various matters herein-after described and claimed.

In the accompanying drawing:

Figure 1 is a perspective view showing an application of my invention;

Figure 2 is a longitudinal section through one embodiment of my top roll;

Figure 3 is a longitudinal section through another embodiment of my top roll; and

Figures 4 and 5 are fragmentary longitudinal sections showing other embodiments of my top roll.

Generally stated, in the illustrated embodiments, I have provided a unit-handling top roll, as T, provided with a sleeve body, as 10, that is rotatably mounted on an arbor or shaft, as 12, through antifriction bearings, as 14, and collars, as 16, demountably secured on the ends of this arbor, are non-rotatably received in non-bottoming and vertically movable relation within vertical slots 17 in a guide bracket G. Mounted in spaced relation on the ends of the sleeve body 10 are spaced cots, as 18, that are peripherally

supported in rolling engagement on similarly positioned bottom roll members R formed on a rotatably driven bottom roll B, and arms 20 of a suitable weighting mechanism press downwardly on these collars 16 to yieldably urge the top roll unit T onto the bottom roll B so that sliver, thread or other suitable intermingled strips of fibers as indicated at S will be subjected to an attenuating operation as it is fed between the top and bottom roll members.

Referring in detail to the embodiment of Figure 2, the sleeve body 10 has enlarged cylindrical end portions forming spaced roll members 11 interconnected by an intermediate necked portion 15 of the sleeve, and these end portions are covered by the cots 18 which may be composed of suitable yieldable material such as cork, leather or rubber. A central bore 22 through the sleeve body 10 opens at its ends into counterbores 24 each of which is provided with an annular shoulder 25 at its inner end. Each bearing 14 is shown as a unit-handling antifriction bearing wherein rolling elements, such as bearing balls, roll in raceways formed in an outer race ring 26 and in an inner race ring 27, each outer race ring 26 being frictionally and demountably seated in one of the counterbores 24 against its end shoulder 25, and each inner race ring 26 slidably and demountably receiving the arbor 12 which extends through the bore 22 in spaced relation to the sleeve 10. To assure ample support for the arbor 12, I preferably have the inner race rings 27 axially extend inwardly towards each other and beyond the outer race rings 26.

Each collar 16 has an outer cylindrical end 30 that extends outwardly from the sleeve body 10 and which is loosely received in one of the guide slots 17 as shown in Fig. 1. A peripheral groove 31 in each collar receives the end of one of the weight arms 20, and a screw, as a dog point set screw 32 removably threaded in the cylindrical end 30 and provided with a stem 33 slidably fitting within a transverse bore in the arbor 12, demountably secures the collar 16 to the end 45 of the arbor. An annular flange 34 on each collar lies in closely spaced relation to the counterbore 24 and serves to prevent the egress of bearing lubricant out of the ends of the top roll and also prevents the ingress of dirt and other deleterious matter to the bearings. To further prevent leakage of lubricant from the bearings 14, the space between the outer ends of each of the race rings 26 and 27 may be provided with annular shields indicated at 35. The bearings 14 are lubricated before assembly in my top-roll

structure and the end collars 16 secure the top roll parts as a unit-handling assembly. However, should the need arise for relubrication or replacement of these bearings it is only necessary to remove one of the set screws 32 whereupon the arbor may be withdrawn and the bearings 14 may then be slidably removed from the counterbores 24. The inner end of each collar 16 has a reduced annular shoulder 36 engageable with the adjacent inner race ring 27, and the collars 16 are so located by the set screws 32 that the space between the shoulders 36 slightly exceeds the distance between the corresponding outer ends of the inner race rings 27 when the outer race rings 26 are both seated against the shoulders 25. With this construction, each bearing may have sufficient axial movement so that it may adjust itself to accommodate slight misalignment of parts, and there is no tendency for the balls to bind in their raceways.

Fig. 3 shows my invention embodying a unit-handling needle bearing 114. In this construction, a sleeve body 100 generally similar to my sleeve body 10 has end counterbores 124 terminating at their inner ends in shoulders 125. Outer race rings 126 of these needle bearings 114 demountably seat within these counterbores against the shoulders 125, and rollers 127 retained within these outer race rings are in freely rolling contact with raceways 128 formed as integral reduced cylindrical projections from end collars 116 corresponding to the collars 16 and secured upon the ends of an arbor 112 by set screws 132. The intermediate portion of each end collar 116 has a conical shoulder 136 engageable with the outer end of the adjacent needle bearing but initially spaced therefrom for the same reason that the corresponding shoulder 36 of Figure 1 is spaced from the bearing 14.

Figure 4 shows another embodiment wherein a unit-handling needle bearing 114 mounted in the sleeve 100 as shown in Fig. 3 has its rolling elements 127 in direct rolling contact with an arbor 212, and end collars 216, secured to reduced ends 213 of the arbor by set screws 232 are adapted to be received in the guide grooves 17 of the guide bracket G. Conical inner end shoulders 236 on the end collars 216 are engageable with the race rings 126 but initially spaced therefrom.

Figure 5 shows my unit-handling top roll using sleeve bearings 314 which may be composed of suitable lubricant impregnated material, such for example, as a molded fibrous material commonly known under the trade name of "Textolite" and impregnated with graphite. The sleeve bearings 314 are respectively fitted in the end counterbores 324 and against the annular shoulders 325 in a sleeve body 310 generally similar to the sleeve 10. The reduced outer ends 313 of an arbor 312 are journalled in the bearings 314, and end collars 316 similar to the collars 216 are demountably fastened by set screws 332 upon the reduced outer ends 313 of the arbor 312.

I claim:

1. In a top roll for textile machinery, a rotatable sleeve body having end counterbores, spaced cots secured to said sleeve body, a unit-handling bearing demountably and non-rotatably seated in each counterbore, a shaft slidably received in said bearings and spaced from said sleeve body, a collar on each end of said shaft and having an inner end projecting into said sleeve body adjacent to one of said bearings, said collars being axially movable into and out of bearing engage-

ment, and means detachably fastening each of said collars to said shaft.

2. A top roll for textile machinery and comprising a rotatable sleeve body having end counterbores, spaced cots mounted on the sleeve body, a pair of unit-handling antifriction bearings, each bearing having an outer race ring demountably seated in one of said counterbores, inner race rings for said bearings, an arbor extending through said sleeve body and demountably supported by said inner race rings in spaced relation to the sleeve body, a collar demountably fastened to each end of said arbor independently of said bearings and extending into the sleeve body, and shoulders on the inner ends of the collars respectively engageable with said inner race rings.

3. In a top roll for textile machinery, a rotatable sleeve body having a through bore, an antifriction bearing demountably seated in each end of said bore, means locating said bearings, an arbor extending in spaced relation through said sleeve body and slidably received by both of said antifriction bearings, a collar on each end of said arbor and having a reduced annular shoulder laterally engageable with one of said antifriction bearings, an intermediate peripheral flange on each collar in closely spaced relation to said bore, and means detachably fastening each of said collars in a predetermined position on said arbor.

4. In a top roll for textile machinery, a rotatable sleeve body, unit-handling bearings demountably received in the ends of said sleeve body, an arbor axially extending through said sleeve body in spaced relation, collars detachably secured to the ends of said arbor, and reduced cylindrical inner end portions on said collars respectively and demountably carried by said bearings.

5. In a top roll for textile machinery, a rotatable sleeve body having end counterbores, an arbor having an intermediate portion of enlarged diameter and end portions of reduced diameter, antifriction bearings demountably seated in said counterbores and demountably receiving the intermediate portion of said shaft, and collars detachably fastened on the reduced end portions of the arbor, said collars projecting out from the ends of the sleeve body and co-operatively securing the antifriction bearings in seated position.

6. In a top roll for textile machinery, a rotatable sleeve body having end counterbores, an arbor extending in spaced relation through said sleeve body and having reduced cylindrical ends, bearings demountably seated in said counterbores and respectively receiving said reduced cylindrical ends, and collars detachably fastened to the reduced arbor ends and extending out of said sleeve body.

7. In a top roll for textile machinery, a shaft, a weight receiving collar secured to each end of the shaft and detachable from the shaft by axially sliding thereon, an elongated sleeve body having spaced cots thereon, the interior of said body having a through bore surrounding and spaced from the shaft, a pair of bearings seated in the bore near the ends of the bore and surrounding said shaft to support the shaft and the body for relative rotation, each collar having a shoulder spaced from but engageable with the outer end of the adjacent bearing to limit the extent of relative axial movement between the body and the shaft, and the shaft being removable from said body and from both bearings by

endwise sliding movement after removal of one of said collars.

8. In a top roll for textile machinery, a rotatable sleeve body having spaced cots on its exterior and having a through bore, a bearing demountably seated in each end of said bore, a shaft extending through said sleeve body and

slidably mounted in said bearings, and collars detachably fastened to the ends of said shaft in axially spaced relation to said bearings and projecting out of the ends of said sleeve, said collars being axially movable into and out of bearing engagement.

LELAND D. COBB.
